UNITED STATES PATENT OFFICE.

SHERIDAN A. VAN HORN, OF SYRACUSE, NEW YORK, ASSIGNOR OF FORTY-NINE ONE-HUNDREDTHS TO MATHEW HALL, OF SYRACUSE, NEW YORK.

WOMAN'S HAT-FASTENER.

1,154,222.

Specification of Letters Patent. Patented Sept. 21, 1915.

Application filed May 29, 1913. Serial No. 770,582.

To all whom it may concern:

Be it known that I, SHERIDAN A. VAN HORN, of Syracuse, in the county of Onondaga and State of New York, have invented 5 a certain new and useful Woman's Hat-Fastener, of which the following is a specification.

This invention has for its object the production of a woman's hat fastener which is 10 particularly simple in construction and highly efficient and durable in use, and it consists in the combinations and constructions hereinafter set forth and claimed.

In describing this invention reference is 15 had to the accompanying drawings in which like characters designate corresponding parts in all the views.

Figure 1 is a cross-sectional view of my 20 hat fastener, the same being shown as applied to a hat. Fig. 2 is a plan of my hat fastener, the jaws thereof being shown in their closed position.

This hat fastener comprises generally a 25 frame adapted to be inserted in the crown of a hat, opposing movable jaws carried by the frame, and a single operative member for controlling the jaws, the operating member extending to the outside of the hat. The 30 jaws are movable toward each other and the operating member is arranged between the jaws and movable rectilinearly in a direction crosswise of the movement of the jaws.

1 is the top plate of the frame; 2 are legs 35 which support the top plate and which rest upon a suitable base 3 in the form of a ring. The frame may be secured in the hat in any suitable manner. The frame is formed of any suitable light material or metal and is in skeleton form in order to be as light as 40 possible.

5 are the opposing jaws which are here shown as pivoted at 6 at their front ends to the top plate 1, these jaws including arms 45 extending rearwardly from the pivots and having depending and inwardly bent prongs 7 and 8 located at their rear ends and intermediate of their ends respectively, the prongs 7 depending at a greater distance below the main arms of the jaws 5 than the intermediate prongs 8 and said prongs passing 50 through openings 9 formed in the legs 2. The jaws are also provided with inwardly and rearwardly extending converging arms 10 which coact with the operating member 55 to be described.

11 is the operating member mounted on the top plate 1 and movable forwardly and rearwardly in substantially the plane of the main arms of the jaws 5, and midway between said jaws, said operating member including a cam 12 having inclining diverging surfaces coacting with the arms 10 and straight surfaces 13 at the high points of the inclined surfaces of the cams, the surfaces 13 forming seats for the arms 10 when the 60 jaws are in open position. The cam 12 is formed with a lengthwise slot 14 which receives a guiding lug 15 projecting from the top plate and having a head 16 which overlies the upper surface of the cam. The cam 12 is also formed with horizontal side flanges 17 which overlie the contiguous portions of the arms 10. The operating member 11 extends to the outside of the hat and is provided with a suitable handle 18 at the outer 65 end.

During movement of the operating member outwardly from its starting position shown in Fig. 2, the diverging surfaces 12 act on the arms 6 to separate the same, and hence force the jaws 5 outwardly into the 70 position shown in Fig. 2, in which position the jaws are held by the seats 13 of the cam. The jaws are controlled in their returning movement by the operating member 11, but 75 after being started, are moved to their closed end.

19 are the springs, and as here shown, these springs connect the jaws 5 and the 80 operating member 11, and during the movement of the operating member from its starting position, shown in Fig. 2, the springs pass from one side of a straight line connecting the points of securement 20 of the springs and the jaws to the other side 85 of said line, and when the operating member 11 has been started on its return movement until the high surfaces 13 of the cam move out of engagement with the arms 6, 90 the springs 19 thereof act in a lengthwise direction on the member 11 and serve to return the operating member to its initial position, the springs at the same time pulling the jaws 5 to their closed position and hence 95 causing the arms 6 to act on the inclined surfaces of the cam 12 to force the member 11 to its starting position.

In operation, the wearer places the hat on her head after pulling rearwardly or outwardly on the handle 18, and after the hat is 110

placed into position the handle 18 is pressed inwardly or forwardly permitting the springs to yieldingly move the jaws 5 toward each other carrying their prongs 7 and 8 into the wearer's hair.

5. What I claim is:

1. A woman's hat fastener comprising a frame adapted to be inserted in the hat, a pair of opposing jaws carried by the frame, an operating member common to both jaws and having a handle located on the outside of the hat, the operating member being movable in a direction transversely of the movement of the jaws, and a spring connecting the jaws and the operating member and arranged to pull the jaws into operative position and to act on the operating member to move the same to its starting position, substantially as and for the purpose set forth.
- 20 2. A woman's hat fastener comprising a frame adapted to be inserted in the hat, opposing pivoted jaws having prongs for entering the hair of the wearer, the jaws being movable on their pivots toward and from each other and having angularly arranged arms extending toward each other, an operating member arranged between the jaws and movable in a direction transversely of the movement of the jaws and having means 30 for coacting with said arms to rock the jaws on their pivots when said member is moved in one direction, and springs for moving the jaws to their closed positions, the springs connecting the jaws and the operating member and being movable from one side to the other of a straight line passing through the points of securement of the springs and the jaws, substantially as and for the purpose set forth.
- 30 3. A woman's hat fastener comprising a frame adapted to be inserted in the hat, opposing pivoted jaws having prongs for entering the hair of the wearer, the jaws being movable on their pivots toward and from each other and having angularly arranged arms extending toward each other, an operating member arranged between the jaws and movable in a direction transversely of the movement of the jaws and having a cam 45 for coacting with said arms to rock the jaws on their pivots, and springs for moving the jaws to their closed positions, the springs connecting the jaws and the operating member and, being movable from one side to the other of a straight line passing through the points of securement of the springs and the jaws, and the cam having seats for engaging said arms when the jaws are in open position for preventing movement of the jaws by the springs substantially as and for the purpose described.
- 60 4. A woman's hat fastener comprising a frame adapted to be inserted in the hat, opposing movable jaws pivoted to the frame and movable toward and from each other,

the jaws having inwardly extending arms, an operating member movable crosswise of the direction of the movement of the jaws and having a cam coacting with said arms, the cam having diverging surfaces, and a spring means tending to move the jaws toward each other, substantially as and for the purpose specified.

5. A woman's hat fastener comprising a frame adapted to be inserted in the hat, opposing movable jaws pivoted to the frame and movable toward and from each other, the jaws having inwardly extending arms, an operating member movable crosswise of the direction of movement of the jaws, and having a cam coacting with said arms, the cam having diverging surfaces, and springs tending to move the jaws toward each other, the springs connecting the jaws and the operating member and being movable from either side to the other of a straight line connecting the points of securement of the springs and the jaws, substantially as and for the purpose set forth.

6. A woman's hat fastener comprising a frame adapted to be inserted in the hat, opposing jaws pivoted to the frame and movable on their pivots toward and from each other, the jaws including horizontally extending arms provided with depending inwardly bent prongs located intermediate the ends of the arms and at the ends of the arms, the prongs at the ends of the arms being located at a greater distance below the arms than the other prongs, and means for controlling the movement of the jaws, substantially as and for the purpose described.

7. A woman's hat fastener comprising a frame adapted to be inserted in the hat, opposing jaws pivoted to the frame and movable on their pivots toward and from each other, the jaws including horizontally extending arms provided with depending inwardly bent prongs located intermediate the ends of the arms and at the ends of the arms, the prongs at the ends of the arms being located at a greater distance below the arms than the other prongs, and means for controlling the movement thereof of the jaws, said means including an operating member arranged in substantially the same level as the horizontal arms of the jaws being movable in a direction crosswise of the movement of the jaws and having a handle located outside of the hat, substantially as and for the purpose specified.

8. A woman's hat fastener comprising a frame adapted to be inserted in the hat, opposing jaws pivoted to the frame and movable on their pivots toward and from each other, the jaws including horizontally extending arms provided with depending inwardly bent prongs located intermediate the ends of the arms and at the ends of the arms, the prongs at the end of the arms being lo-

cated at a greater distance below the arms than the other prongs, and an operating member having means for coacting with the arms for controlling the movement thereof,
5 the operating member being arranged in substantially the same level as the horizontal arms of the jaws, and being movable in a direction crosswise of the movement of the jaws and having a handle located outside of
10 the hat, and springs connecting the arms of the jaws to the operating member and tending to move and hold the jaws in their closed

position and to move the operating member toward its starting position, substantially as and for the purpose set forth.

15

In testimony whereof, I have hereunto signed my name in the presence of two attesting witnesses, at Syracuse, the county of Onondaga, in the State of New York, this 5th day of May, 1913.
